(57) **CLAIM**

The ornamental design for a shoe sole, as shown and described.

DESCRIPTION

FIG. 1 is a lateral perspective view of a shoe sole showing our new design;

FIG. 2 is a front view thereof;

FIG. 3 is a rear view thereof;

FIG. 4 is a lateral side view thereof;

FIG. 5 is a medial view thereof;

FIG. 6 is a top view thereof;

FIG. 7 is a bottom view thereof; and,

FIG. 8 is a medial perspective view thereof.

The broken lines immediately adjacent the shaded areas represent the bounds of the claimed design while all other broken lines are directed to environment and portions of the shoe sole that are not claimed, and are for illustrative purposes only. The broken lines and structure they depict form no part of the claimed design.

1 Claim, 8 Drawing Sheets
